TREATMENT OF HYDROCARBON OIL

Wright W. Gary, Great Neck, N. Y., assignor to
 Gasoline Products Company, Inc., Newark,
 N. J., a corporation of Delaware

Application February 1, 1933, Serial No. 654,569

4 Claims. (Cl. 196—49)

This invention relates to the pyrolytic decomposition of hydrocarbon oil, more particularly petroleum and petroleum oils, for the recovery of valuable products, such as gasoline or naphtha, 5 therefrom.

I have observed that residual oils or tars resulting from the pyrolytic decomposition of virgin stocks, such as crude petroleum or virgin gas oil, contain constituents which, while of high 10 specific gravity, are not necessarily the lowest boiling constituents of such residues or tars, and are capable of being subjected to further cracking without excessive coke formation.

My invention therefore has for an object the provision of an improved process of and apparatus for effecting pyrolytic decomposition of petroleum oils, in which a separation of constituents is effected in such manner as to permit further cracking, while avoiding excessive coke formation, and has for further objects such additional improvements in operative advantages and results as may be found to obtain in the process and apparatus hereinafter set forth and claimed.

According to my invention, I effect the pyrolytic decomposition of a virgin stock in a plurality of mild cracking stages, the residue or tar from each stage, after evaporation of a portion of the lower boiling constituents thereof, being delivered to a subsequent stage and there mildly 25 cracked, the products being evaporated and the unvaporized residue being further cracked, until a residue of a predetermined specific gravity, for example, a specific gravity of 0° A. P. I., is obtained.

Preferably, the treated products from the several stages are delivered to a common evaporator, the resultant vapors being combined and delivered to a common fractionating tower to produce a composite stock suitable for further cracking 30 under relatively drastic conditions, while the several residual oils or tars are segregated and separately subjected to further cracking, as has been indicated hereinabove.

Preferably, the temperature conditions maintained in the several cracking operations are moderate in character, such as will produce a mild cracking or "viscosity breaking" effect rather than a drastic cracking of the oil being treated. Each one of the series of cracking operations may be carried out at a temperature somewhat higher than that of the preceding operation. For example, a series of three cracking operations may be carried out at temperatures approximating 860° F., 870° F. and 880° F., respectively, at a

pressure of, say, 250 pounds per square inch in each instance.

On the other hand, it may be preferable in many instances to carry out the several cracking operations at approximately the same temperature, the times of contact in the several operations being successively increased, if desired.

My invention also contemplates flashing the ultimate tar or residual oil from the evaporator under a reduced pressure, the pressure in the evaporator being preferably relatively close to the pressure or pressures maintained in the several mild cracking operations, and fractionation of the vapors liberated in the evaporation and flashing stages in the usual manner.

Such fractionation may be so carried out as to produce a composite stock suitable as a charging stock for a relatively drastic cracking operation, such for example as a vapor-phase cracking operation carried out at a temperature of, for example, from 900° to 1000° F. and an elevated pressure of, say, 250 pounds per square inch. In the preferred instance, such an operation is combined with the operations previously described, the treated products from the drastic cracking 20 operation also being delivered to the common evaporator for the products from the several mild cracking operations.

In its apparatus aspect, my invention contemplates the provision of an evaporator comprising 30 a plurality of sections adapted to receive products from a plurality of cracking coils, and having trap-out trays or other suitable means for segregating and drawing off residual oil or tar from each of said sections and conveying it to the 35 heating coil discharging into the following section.

In order that my invention may be clearly set forth and understood, I now describe, with reference to the drawing accompanying and forming a part of this specification, a preferred form and manner in which my invention may be practiced and embodied. In this drawing, the single figure is a more or less diagrammatic view of apparatus for effecting pyrolytic decomposition 40 of hydrocarbon oil in accordance with my present invention.

Referring to the drawing, a hydrocarbon oil, such for example as a crude petroleum or a virgin gas oil, is drawn from a suitable source, (not 50 shown), through a conduit 1 and delivered by means of a pump 2 and a conduit 3 to a heat exchange coil 4 located in the upper part of a fractionating tower 5. In the coil 4, the oil is pre-heated by heat exchange with vapors in the 55

tower 5, and the preheated oil then passes through a conduit 6 and a branch conduit 7 having a valve 8 to an evaporator 9.

The evaporator 9 is provided with a plurality of trap-out trays 11, 12 and 13, which divide the tower into a plurality of sections 14, 15, 16 and 17. Each of said sections may be provided, as shown, with baffle plates 18, located in the upper part thereof.

10 Fresh oil is discharged into the upper section 14 through the conduit 7, and is then stripped of its volatile constituents, leaving a residue comprising a reduced crude or a tar, which is drawn from the trap-out tray 11 through a conduit 21 and forced by means of a pump 22 through a cracking furnace 23, where it passes through tubes or other heating units (not shown) in which it is subjected to a cracking temperature, preferably under an elevated pressure.

20 The treated products from the cracking furnace 23 are discharged through a conduit 24 having a valve 25 into the section 15 of the evaporator 9 underlying the trap-out tray 11, preferably at a point just below the baffle plate 18. 25 Here evaporation of the lighter constituents occurs, the evaporated materials passing off in vapor form, leaving a residue or tar which collects upon and is withdrawn from the trap-out tray 12 by means of a conduit 26.

30 The residual oil or tar from the trap-out tray is delivered through the conduit 26 by means of a pump 27 to a second cracking furnace 28, where it is subjected to cracking conditions, and the cracked products pass through a conduit 29 having a valve 30 to the next section 16 of the evaporator 9. Here evaporation and separation of lighter constituents take place, and the residue or tar is withdrawn from the trap-out tray 13 through a conduit 32 and delivered by means 40 of a pump 33 to a third cracking furnace 34.

In the furnace 34, the residue or tar from the trap-out tray 13 is subjected to cracking conditions, and the cracked products pass through a line 35 having a valve 36 to the bottom section 17 of the evaporator 9.

45 The combined vapors from the several sections 14, 15, 16 and 17 of the evaporator 9 pass through a vapor line 40 to the lower part of the fractionating tower 5, the interior of which is provided with plates or trays 41 of conventional type. Under the influence of reflux condensate obtained by heat exchange with the oil passing through the coil 4, fractionation of the vapors takes place, heavier constituents of the vapors being condensed and collected in the bottom of the tower 5, from which they may be removed through a drawoff line 42 having a valve 43.

50 Uncondensed vapors reaching the top of the tower 5 pass through a vapor line 45 to a condenser 46, and the cooled products pass through a conduit 51 to a separator 52. The condensate, comprising light distillate is withdrawn from the separator 52 through a condensate line 53 having a valve 54, while uncondensed gas passes off 55 through a gas line 55 having a valve 56.

60 The composite stock withdrawn from the bottom of the tower 5 is preferably delivered through the conduit 42 by means of a pump 61 and a conduit 62 having a valve 63 to a cracking furnace 64, wherein it is subjected to cracking conditions, preferably of a more drastic character than those maintained in the furnaces 23, 28 and 34. The cracked products pass through a transfer line 65 having a valve 66 to the bottom 75 section 17 of the evaporator 9. Vapors from the

cracked products from the furnace 64 pass upward through the evaporator 5, while the residual oil collects in the bottom of the evaporator 5 with the residue from the products from the furnace 34.

5 A portion of the charging stock withdrawn from the tower 5 may be withdrawn through a branch conduit 71 and delivered through valved inlets 72, 73, 74 and 75 to the baffle plates 18 located in the various sections of the evaporator 10 5. The number of sections thus supplied with reflux oil may be varied as desired. Fresh oil may be supplied as reflux to the baffle plates 18 in the sections 15 and 16 of the evaporator 5 through valved branch lines 76 and 77 communicating 15 with the conduit 6.

Where, as in the preferred instance, the evaporator 5 is maintained under an elevated pressure of from 50 to 250 pounds per square inch, for example, 200 pounds per square inch, the tar 20 collecting in the bottom of the evaporator 5 may be flashed under a lower pressure to remove lighter constituents. Thus, the tar from the bottom of the evaporator 5 may pass through a conduit 81 having a pressure-reducing valve 82 to 25 a flash tower 83, maintained under a relatively low pressure of for example from atmospheric pressure to a pressure of 50 pounds per square inch.

30 In the flash tower 83, the tar from the evaporator 5 is flashed under a reduced pressure, as aforesaid, and the final residue or tar is removed through a draw-off line 84 having a valve 85. The liberated vapors, which leave the top of the flash tower 83 through a vapor line 86, may pass 35 through a line 87 having a valve 88 to a condenser 89. The cooled products then pass through a conduit 91 to a separator 92, from which condensate may be withdrawn through a conduit 93 having a valve 94 and pumped to the tower 5, by a pump 40 95, while gases are withdrawn through a conduit 96 having a valve 97.

45 As an alternative mode of procedure, the vapors from the flash tower 83 may pass through conduits 86 and 101, the latter having a valve 102, 45 to a bubble tower 103, where they are fractionated. Uncondensed vapors then pass through a vapor line 104 to a condenser 105, and the cooled products are delivered through a pipe 106 to a separator 107 having a valved gas offtake 108. 50 Condensate leaves the separator 107 through a conduit 109 having a branch 111 provided with a valve 112 and a pump 113 for delivering a part 55 of the condensate to the tower 103 as reflux, while the remainder of the condensate is withdrawn through a branch conduit 114 having a valve 115 for storage or further treatment, as desired.

60 Relatively heavy oil collecting in the bottom of the bubble tower 103 is withdrawn therefrom through a draw-off line 121 having a branch line 122 provided with a valve 123 and leading to storage and a branch line 124 having a valve 125 leading to the conduit 42 on the intake side of the pump 61. Thus, all or a portion of this oil 65 may be delivered to the cracking furnace 64 or as reflux to the evaporator 9, together with oil from the tower 5.

70 While the temperatures and pressures employed throughout the system will vary with the nature of the particular charging stock and the nature of the results desired, I ordinarily prefer to so regulate the conditions of temperature and pressure within the furnaces 23, 28 and 34 that cracking takes place to substantially the same 75.

extent in each furnace. Thus, the temperatures to which the oils are subjected in the furnaces 23, 28 and 34 may be successively increased. On the other hand, the temperatures maintained in these 5 furnaces may be substantially identical, in which case I prefer to employ relatively and successively increasing times of contact, and in any event, I prefer to maintain such conditions in these furnaces that only a mild cracking effect is produced 10 in each, preferably from 6 to 8 percent and not over 12 percent in any case "crack per pass" (i. e. percent of gasoline produced per pass).

Thus, in a particular instance in which the material supplied through the conduit 1 comprises a virgin gas oil having a specific gravity of 34° A. P. I., the oil passing through the cracking furnace 23 may be brought to a temperature of about 860° F., while the oil passing through the cracking furnace 28 may be brought to a somewhat 20 what higher temperature of for example about 870° F., and the oil passing through the cracking furnace 34 may be brought to a still higher temperature of for example about 880° F. Or the temperatures maintained in the furnaces 23, 25 28 and 34 may be similar, for example about 860° F., the times of contact being preferably increased and in any event so regulated that a mild cracking effect is produced in each furnace.

In general, due to the fact that the material 30 charged into each of the furnaces 23, 28 and 34 comprises principally a residual material, the cracking conditions which are maintained in the furnaces 23, 28 and 34 are of a mild nature, for example, within the range commonly employed 35 for "viscosity-breaking" operations and effective to produce a limited amount of cracking without causing an undesirable coke formation.

On the other hand, the temperatures maintained in the furnace 64 are preferably considerably 40 more drastic and may for example be of the order of from 950° to 1000° F., the operation thus taking place in the vapor phase and the cracking effect being considerably greater than that which takes place in the furnaces 23, 28 45 and 34.

In the instance cited, the pressures maintained in the various cracking furnaces are suitably elevated and may be of the order of 250 pounds per 50 square inch, while the evaporator 9 is maintained under a slightly lower pressure of, for example, 200 pounds per square inch, as aforesaid.

While I have shown three mild cracking operations carried out in the furnaces 23, 28 and 34 respectively, I do not limit myself to any particular 55 number of individual cracking operations, the actual number being governed by the nature of the material charged and the nature of the cracked products. In the specific instance mentioned hereinabove, however, the residual materials withdrawn from the trap-out trays 11, 12 and 13 may have specific gravities of 26°, 20° and 12° respectively, while the tar withdrawn through the conduit 81 from the bottom section 17 of the evaporator 9 may have a specific gravity of approximately 0° A. P. I.

It will be obvious to those skilled in the art that while I have described my invention hereinabove with reference to one or more specific illustrative examples and embodiments my invention 70 is not limited to the specific details of such illustrative examples, but may variously be practiced and embodied within the scope of the claims hereinafter made.

I claim:

75 1. Apparatus for the treatment of hydrocarbon

oil, comprising a vertical evaporator tower having a plurality of vertically displaced trap-out trays therein, means for introducing charging oil into an upper level in said tower above a first one of said trap-out trays, means for removing liquid from said trap-out tray, raising it to a cracking temperature and introducing it into said tower below said first trap-out tray and above a second trap-out tray, means for removing liquid oil from said second trap-out tray, raising it to a cracking temperature and returning it to said tower at a point below said second trap-out tray, and means for removing vapors from said tower at a point above said first trap-out tray.

2. The improvement in the process of pyrolytically decomposing hydrocarbon oil which comprises delivering heated oil to an evaporation zone in which vapors are free to pass upwardly while separate pools of oil are collected at vertically-spaced intervals in said zone out of the path of travel of said vapors, withdrawing oil collected from one of said pools, directly from said evaporating zone and passing it in a stream of restricted cross-sectional area through a first heating zone wherein it is raised to a cracking temperature and subjected to conversion, discharging the resultant stream of cracked products into said evaporation zone at a point below said one of said pools, whereby cracked residual liquids from said first heating zone are prevented from returning to said first heating zone, withdrawing oil from a still lower one of said pools, passing it in a stream of restricted cross-sectional area through a second heating zone wherein it is raised to a cracking temperature and subjected to conversion, and discharging the resultant stream of cracked products into said evaporation zone below said lower one of said pools, whereby cracked residual liquids from said second heating zone are prevented from returning to said second heating zone.

3. The process of treating hydrocarbon oil which comprises discharging preheated relatively heavy oil into a first separating zone wherein vapors separate from liquid residue, removing said vapors and forming a desired distillate therefrom, removing liquid residue from said first separating zone at such a rate as to prevent the accumulation of a large body of liquid therein and passing liquid so removed directly through a cracking zone, in a stream of restricted cross-sectional area, wherein it is raised to a cracking temperature and subjected to conversion, introducing resulting hot products of conversion into a second separating zone wherein vapors separate from liquid residue, passing vapors from said second separating zone into said first separating zone, while excluding said vapors from said cracking zone, removing liquid residue from said second separating zone at such a rate as to prevent the accumulation of a large body of liquid therein, passing liquid so withdrawn directly through a second cracking zone in a stream of restricted cross-sectional area wherein it is raised to a cracking temperature and subjected to conversion, introducing resulting hot products of conversion into a third separating zone wherein vapors separate from liquid residue, passing vapors from said third separating zone into said second separating zone while excluding said vapors from said second cracking zone and removing liquid residue from said third separating zone.

4. The process of treating hydrocarbon oil which comprises discharging preheated relatively heavy oil into a first separating zone wherein

vapors separate from liquid residue, removing
5 said vapors and forming a desired distillate
therefrom, removing liquid residue from said first
separating zone and passing it through a crack-
ing zone wherein it is raised to a cracking tem-
perature and subjected to conversion, introduc-
10 ing resulting hot products of conversion into a
second separating zone wherein vapors separate
from liquid residue, passing vapors from said sec-
ond separating zone into said first separating
15 zone, while excluding said vapors from said
cracking zone, removing liquid residue from said
second separating zone, passing it through a sec-
ond cracking zone, in a stream of restricted cross-
sectional area, wherein it is raised to a cracking
temperature and subjected to conversion, introduc-
15 ing hot products of conversion into a third
separating zone wherein vapors separate from

liquid residue, passing vapors from said third
separating zone into said second separating zone,
while excluding said vapors from said second
cracking zone, removing liquid residue from said
third separating zone and introducing it into a 5
flashing zone under reduced pressure to cause ad-
ditional vaporization thereof, fractionating re-
sulting vapors to form a clean condensate charg-
ing stock, passing said clean condensate charg-
ing stock through a third cracking zone wherein 10
it is raised to a vapor phase cracking tempera-
ture and subjected to conversion, separating re-
sulting hot products into vapors and a liquid
residue in a fourth separating zone and passing
vapors from said fourth separating zone into 15
said third separating zone.

WRIGHT W. GARY.
